(57) **CLAIM**

The ornamental design for a modular sleeping unit, as shown and described.

DESCRIPTION

FIG. 1 is a perspective view of a modular sleeping unit showing our new design;

FIG. 2 is a front view thereof;

FIG. 3 is a rear view thereof;

FIG. 4 is a right side view thereof;

FIG. 5 is a left side view thereof;

FIG. 6 is a cross-sectional view at 6-6 in FIGS. 4 and 5;

FIG. 7 is a cross-sectional view at 7-7 in FIGS. 4 and 5 showing the desk in a closed position;

FIG. 8 is an internal perspective view thereof facing the right internal wall of the modular sleeping unit showing the desk in an open position; and,

FIG. 9 is an internal perspective view thereof facing the left internal wall of the modular sleeping unit showing the desk in an open position.

The broken line showing of window shades in FIGS. 6, 7, 8, and 9 is included for the purpose of showing environmental portions of the modular sleeping unit and forms no part of the claimed design.
